UNITED STATES PATENT OFFICE.

HYMAN ELI GOLDBERG, OF CHICAGO, ILLINOIS, ASSIGNOR TO GOLDBERG CALCULATING MACHINE COMPANY, OF CHICAGO, ILLINOIS.

CALCULATING-MACHINE.

1,276,520.

Specification of Letters Patent. Patented Aug. 20, 1918.

Application filed September 9, 1911. Serial No. 648,540.

To all whom it may concern:

Be it known that I, HYMAN ELI GOLDBERG, a citizen of the United States, residing at Chicago, in the county of Cook and 5 State of Illinois, have invented certain new and useful Improvements in Calculating-Machines, of which the following is a specification.

My invention is an improvement in calculators attached to typewriters and more particularly to the calculator known as the Wahl adding machine now on the market in connection with the Remington typewriter. By means of this calculator it is possible to add 10 numbers arranged on the paper in a vertical column. But the calculator as now constructed is not adapted for the addition of numbers arranged upon the paper in a horizontal line, although mechanism illustrating. 15 the addition of numbers so arranged is described in several patents, among them Patent No. 893,717, issued to John C. Wahl, July 21, 1908. One of the main objects of my invention has been the modification of 20 the calculator to adapt it to the above mentioned horizontal addition of numbers with but few changes of its parts.

The invention is illustrated by the drawings of which—

30 Fig. 1 represents a front elevation of the adding and subtracting calculator mounted upon a typewriter, (namely the Wahl calculator mounted upon the Remington visible typewriter).

35 Fig. 2 represents a fragmentary plan view of the same, and

Fig. 3, an end elevation thereof.

Fig. 4 is an enlarged view of a detail.

To represent the typewriter there is shown 40 the framework 1, on which is mounted the carriage 2, and the keys 3. Of course there are supposed to be present the type bars, connecting mechanism, platen, escapement mechanism and all other parts which enter 45 into the construction of a typewriter. But as they form no part of the invention and are old in the art they are left out in the illustrations.

To represent the adding and subtracting 50 calculator there is present the master mechanism 4, mounted on the framework 1. The master mechanism is suitably connected to and operated by the numeral keys 3 of the typewriter. The master mechanism operates 55 the totalizer 5 which is suitably mounted

upon a truck 6, which in turn is carried by the arms 7, attached to the carriage 2. The totalizer is locked in place by being bolted to the rack 8 which is fastened to the truck. When the keys of the typewriter are operated, the carriage travels to space the letters, and carries the truck along. The truck in turn carries the totalizer past the master mechanism which also is operated by the keys. This too then receives the numbers 60 impressed upon the numeral keys. The above mechanism is old and fully described in the Patent No. 893,719 above cited, and therefore will not be given in any greater detail. 65

In the mechanism of my invention there are added two brackets 10—10, fastened to the framework. Rotatably mounted in the brackets is a shaft 11 which has a keyway 12 cut therein. Mounted on the shaft 11 is 70 the reciprocator 13 which has a feather 14 to engage the keyway 12. The reciprocator 13 is continually pulled to the right by means of a spring 15 which is fastened by its one end to the reciprocator and by its other end 75 to the framework. If there were no resistance, the reciprocator 13 would be moved to the right where it would stop against a spring 16, which is wound around the right end of the shaft 11 above mentioned. This 80 spring 16 has its one end inserted in the keyway 12 and the other end fastened to bracket 10. The spring is thus able to accomplish two functions, the one just mentioned, 85 namely to prevent the reciprocator 13 from being pulled too far to the right, and the other namely to give the shaft 11 a tendency 90 to rotate its top portion forward.

The front end of the reciprocator 13 is 95 provided with a bolt 20, which by the combined action of the two springs 15 and 16 thus has a tendency to move both downward and to the right. This tendency is resisted by a rider 21 projecting from the reciprocator continually riding upon the track 22 forming part of the framework. Normally the bolt 20 is in its down position, but when the reciprocator 13 occupies its position at the extreme right or at the extreme left, then the rider 21 has ridden up on the hill 100 23 or 24 respectively (best seen in Fig. 2) and the bolt 20 has therefore been raised to its elevated position.

In Figs. 1 and 2 are represented three 105 totalizers mounted on the truck, a dotted

one at the right, a dotted one at the left and one drawn in full lines at the middle. The two end totalizers are fastened to the truck in the manner described in Patent No. 5 893,719 above cited. That is, they are rigidly fastened to the truck and during the operation of the machine are carried along therewith. They will therefore be called the fixed totalizers. The middle totalizer is 10 not rigidly fixed on the truck but can be reciprocated thereon. It will therefore be called the reciprocating totalizer. Its construction has been modified as follows. The bolt by means of which each of the fixed 15 totalizers is held upon the truck has been removed and in its place has been substituted a latch 30 (best shown in Fig. 4). This latch is carried by a bar 31, which is mounted upon and forms a part of the framework 20 of the totalizer. This latch 30 is continually pressed by a spring 32 to contact with the rack 8 above mentioned in which rack there have been cut a series of beveled notches 33 to coöperate with said latch 30. It is evident 25 that the construction shown permits the sliding to the left of the totalizer upon the bar, but prevents any sliding to the right. Fastened to the top and forming part of the latch 30 is the finger 41, by means of which 30 said latch can be opened so as not to engage the notches to release the top from the truck. To coöperate with said finger 32 is a tripper 42 fastened to the framework, the result being that whenever the totalizer is carried 35 past the tripper 42 the latch is opened and the totalizer disengaged from the rack.

Mounted upon the top of the totalizer is a catch 50, which has an incline 51 formed upon its right side, a similar incline 52 formed upon its left side, and at its center a cut 53, the edges of which are beveled as shown at 54. This catch 50 is intended for the reception of the reciprocator bolt 20 of the reciprocator above described.

45 The operation of the mechanism is as follows: Assume that the carriage is in its extreme position at the right and that the reciprocating totalizer occupies upon the truck its extreme position at the left, that is, in 50 contact with the fixed totalizer mounted upon the left end of the truck. As the carriage of the typewriter advances to the left, because of the operation of the typewriter keys, or otherwise, the left fixed totalizer is 55 carried past the master mechanism. During this period the keys might be operated for letters or numbers. All this while the middle totalizer has been carried along by its latch which is engaged with the notch 33. 60 As the carriage advances further the incline 52 of the notch 50 passes under the reciprocating bolt 20 and lifts it up. As the motion of the truck and totalizer continues the bolt 20 passes over the bevel 54 and drops into 65 the cut 53 and from there on the recipro-

cator is pulled along by the totalizer against the force of the spring 15. The motion of the carriage continues until the latch finger 42 comes in contact with the tripper 41 above described. This releases the latch and totalizer upon the truck whereupon the spring 15 immediately pulls the reciprocator and totalizer back to the right until further motion is stopped by the engagement of the latch with the notch 33 next to the right. 70 As the motion of the carriage continues, the totalizer is again carried to the left, its latch again opened, and the reciprocator and totalizer again jump to the right. And so on, until in its last jump the middle totalizer 75 comes in contact with the fixed totalizer mounted on the right end of the truck. As the motion of the carriage continues the middle totalizer again passes the tripper 42 and the latch is again opened, but now the 80 totalizer cannot be drawn back to the right. The middle totalizer is therefore carried along farther to the left than it would have gone if the fixed totalizer had not been present. The reciprocator also is carried farther 85 to the left than it has yet been carried. This continues until during such further motion of the reciprocator the rider 21 climbs up on the hill 24 above mentioned. The bolt 20 is thereupon lifted out from the 90 cut 53 whereupon the reciprocator is immediately drawn to the right. The totalizer however is carried still farther to the left by the motion of the carriage, and such motion may be of any extent. It is thus possible for the totalizer mounted upon the 95 right end of the truck to reach and be operated on and even pass by the master mechanism. Thus words may be written to the right of the right totalizer. 100

The carriage is now returned to the right ready for the writing of the next line. During said return the fixed totalizer mounted on the right end of the truck passes over the master mechanism. The middle 105 totalizer now adjacent to the fixed totalizer at the right then comes in contact with the bolt 20 by means of the bevel 51 formed upon the catch 50. The motion of the carriage to the right continues. The catch 50 will therefore either lift up the bolt 20 of the reciprocator, which will thereupon drop into the cut 53 thus engaging the totalizer and preventing any further motion thereof to the right, or should it happen that the totalizer 110 moves very freely upon the truck then the resistance of the bolt 20 to being lifted might be sufficient to shift the totalizer on the truck. In either case, the further progress to the right of the middle totalizer 115 is resisted, which resistance compels the totalizer to slide on the truck, the latch clicking over the notches formed in the rack bar. Further motion to the right of the truck 120 now brings the left fixed totalizer against 125 the right end of the truck, which brings the 130

the middle totalizer and compels the middle totalizer to travel to the right along with the truck. During all this time the reciprocator occupied its normal position, that is, it abutted against the spring 16. The continued further motion of the middle totalizer, which meanwhile has engaged the bolt 20, now compels the reciprocator to move still farther to the right, compressing the spring 16. This compulsory motion of the reciprocator to the right of its normal position continues until its rider 21 climbs up on the hill 23 which thereupon disengages the bolt 20 from the totalizer. The totalizer then is carried along farther to the right without any further interference from the reciprocator. The reciprocator immediately returns to its normal position under the influence of the spring 16. The further motion of the carriage now carries the left totalizer past the master mechanism, and the carriage is then in the starting position again.

It will be noticed that the return of the carriage automatically returns the middle totalizer to its position at the left end of the truck thus locating it ready for any numbers that might be written at the left side of the sheet of paper. Moreover, while in this position it is locked by its latch engaging the notch thus preventing it from being shifted toward the right while the fixed totalizer toward the left prevents any motion toward the left. In this position it is retained until the totalizer mechanism comes into play and operates it as above described.

While in the drawings there has been illustrated a jumping middle totalizer with a fixed totalizer toward the right and another fixed totalizer toward the left, it is evident that these fixed totalizers can be replaced by any form of fixed stop in so far as their action upon the reciprocating totalizer is concerned. In many cases, particularly when words are to be written on the paper immediately adjacent to the zone of action of the reciprocating totalizer, some form of stop might be preferable to the fixed totalizer, as occupying less room. Such stops are now put on the market in connection with the Wahl adding machine and they are quite narrow, occupying but one space in width. It will thus be seen that if there is a column of figures to be added immediately to the right or to the left of the zone of action of the middle totalizer then such a column can be added by means of a fixed totalizer which serves the double function of totalizer for the column and a stop for the jumping totalizer. If there is no column of figures immediately adjacent to the zone of action of the jumping totalizer, then such a fixed totalizer may be replaced by any form of stop.

While in the illustration there has been shown only one jumping totalizer mounted upon the truck, it is perfectly evident that on long trucks there might be several, each operative within its own zone of reciprocation, the zone being delimited by the stops mounted on each side of the totalizer. The reciprocator will coöperate first with one jumping totalizer, then as the totalizer is carried too far away, the reciprocator will coöperate with the next jumping totalizer, etc. This is one of the principal features of my invention. As far as I am aware, it is new to provide means whereby more than one jumping totalizer may be operated on the same calculating machine.

In the drawings accompanying this specification, the typewriter is of the Remington type, that is, the paper moves while the type basket is stationary. Of course this might easily be modified without departing from the spirit of my invention. For instance, the paper might be stationary while the type basket might move. In either case, there is always some part that moves continually in order to determine upon the paper the location for the printing of the figures. And that particular part or anything that moves in unison therewith I call the printing carriage. In the mechanism here described the printing carriage may therefore be considered to be the carriage of the typewriter or the truck or any part that continually travels in unison therewith. For instance the rack fastened to the truck may be called the printing carriage.

In the drawings accompanying this specification and in the mechanism described there has been shown a reciprocating totalizer. This is the form in which the calculating machine has been put on the market in connection with the Remington typewriter. Of course it is understood that should the typewriter be of a different class, for instance a book typewriter like the Elliott-Fisher machine, then the mechanism would naturally be changed therewith, and the totalizer would probably be stationary while the parts above described as stationary would reciprocate. In fact, calculating machines in connection with typewriters might loosely be subdivided into three classes:

1. Those in which the master wheel is stationary while the totalizer travels relatively thereto.
  2. Those in which the totalizer is stationary while the master wheel travels relatively thereto.
  3. Those in which there is no master wheel proper, its place having been taken by other mechanisms, as some sort of traveling trigger determining the place of the calculation.
- But in all of these classes there is always some piece traveling relatively to another, and the position of this piece determines the

decimal place of calculating in the calculating machine. I therefore call this traveling piece the decimal carriage. This decimal carriage may therefore be a totalizer, a master wheel or a trigger, the name decimal carriage being applied to it because of its function of determining the decimal place of the calculating independent of other additional functions it may possess. In this machine, 10 the decimal carriage is the traveling totalizer.

Reviewing, it will be seen that in the machine embodying my invention two distinct mechanisms come into play at different 15 times. One is the means for releasing the totalizer by the tripper, permitting it to be drawn back to the right ready to be carried along to the left to receive the next number. This is old in the art. The other 20 is the mechanism whereby the totalizer is disconnected from the reciprocator at each extreme of the motion of the latter. This might be described as a means rendering the jumping mechanism inoperative when carried beyond its zone of action. Again it 25 might be described as a means for rendering the jumping mechanism operative within its zone of action.

Another way of expressing the same thing 30 might be employed. It might be said that the reciprocator and totalizer become disengaged from each other at either extreme of their travel. That is, the reciprocator becomes disengaged from the totalizer at either 35 extreme of the travel of the reciprocator or again, considering it from another standpoint, the reciprocator becomes disengaged from the totalizer at either extreme of the travel of the totalizer. Similarly, the same 40 statement would apply if the words decimal carriage be substituted in the immediately preceding sentences for the word totalizer.

The mechanism shows a bolt upon the reciprocator and a catch upon the totalizer. 45 It is perfectly evident that it would be nothing but a mechanical equivalent to reverse their positions and to place the bolt upon the totalizer or the decimal carriage and the catch upon the reciprocator. Moreover, it is 50 not necessary that the bolt be lifted from the catch. The catch might just as well be lifted away from the bolt and therefore I do not wish to limit myself to the particular location of either the bolt or the catch or the 55 particular means of disconnecting one from the other.

The drawings and specification show that the bolt of the reciprocator is disconnected from the catch of the totalizer by the bolt 60 riding up a stationary incline or hill. This construction can be varied without departing from the spirit of my invention. There would be no difficulty in shifting the hill from the frame to the truck which hill 65 would therefore at a predetermined period

come in contact with an arm fixed to the reciprocating shaft and operate the latter to lift the reciprocator bolt from the totalizer catch. It is thus seen that it is not necessary that the hill be stationary. It 70 might be made to travel.

The drawings show a mechanism whereby a fixed stop (the fixed totalizer) comes in contact with a reciprocator totalizer, and carries it to an extreme position whereby 75 the reciprocator itself is carried to an extreme position, and riding up upon the hill lifts the bolt from the catch. The action of the fixed stop upon the reciprocator to disconnect it from the totalizer is therefore 80 indirect. The mechanism pointed out in the last paragraph shows that it need not be indirect but may be direct. Attention is called to the fact that it is really the fixed stop upon the traveling truck that causes 85 said disconnecting of the reciprocator and decimal carriage, for if the stop were not there, such disconnecting would not occur.

The drawings show a master mechanism 90 which has only one master wheel. But my invention can easily be applied to a master mechanism which includes therein more than one master wheel, like the one shown in Patent No. 893,722, issued to me July 21, 95 1908.

Employing such a plurality of master wheels, it is evident that the parts may be so arranged that the reciprocatory totalizer will reciprocate in front of one master wheel while the fixed totalizer at the right will not 100 yet have reached any master wheel, although it is continually approaching nearer and nearer thereto. This condition persists during the travel of the carriage through its zone of horizontal addition. After the carriage reaches the end of its zone, the reciprocatory totalizer will be carried out of its 105 reciprocatory latitude and will now reach the second master wheel, while the fixed totalizer at the right will now reach the first master wheel, that is, the one previously operating the reciprocatory totalizer. As shown in the above cited Patent No. 893,722, the second master wheel subtracts, when the first master wheel adds. The operating of the machine 110 will therefore cause the number now appearing in the reciprocatory totalizer to be subtracted therefrom and to be simultaneously added into the fixed totalizer at the right. In other words, the totals computed by the reciprocatory totalizer will now be transferred into the fixed totalizer, which 115 may therefore be called the grand totalizer.

It will thus be seen that without any 120 change in my invention, but simply by combining it with mechanism already shown in patents previously issued to me, it may be used to compute quite a variety of calculations of which one has just above been given 125 as an illustration.

I claim—

1. In a machine adapted for calculating and horizontal printing: a decimal carriage traveling to locate the calculating point; a printing carriage, traveling to locate the printing point, and including in its travel a zone of horizontal addition; a reciprocator relatively movable to said printing carriage to reciprocate the decimal carriage for the calculating of the horizontally printed numbers and traveling at the same rate as said decimal carriage; the reciprocator coöperating relatively movable to said printing carriage coöperating with the decimal carriage within the zone but not coöperating there-
10 bers and traveling at the same rate as said decimal carriage; mechanism for disconnecting the decimal carriage and the reciprocator when the decimal carriage is moved to an extreme position, and means to move said reciprocator relative to said printing carriage.
15 2. In a machine adapted for calculating and horizontal printing: a decimal carriage traveling to locate the calculating point; a printing carriage traveling to locate the printing point, and including in its travel a zone of horizontal addition; a reciprocator relatively movable to said printing car-
20 rriage to reciprocate the decimal carriage for the calculating of the horizontally printed numbers and traveling at the same rate as said decimal carriage; mechanism automatically connecting the reciprocator and
25 the decimal carriage within said zone and disconnecting them without said zone, and means to move said reciprocator relative to said printing carriage.
30 3. In a machine adapted for calculating and horizontal printing: a decimal carriage traveling to locate the calculating point, a printing carriage traveling to locate the printing point, and including in its travel a zone of horizontal addition; a reciprocator relatively movable to said printing carriage to reciprocate the decimal carriage for the calculating of the horizontally printed numbers and traveling at the same rate as said decimal carriage; a bolt and catch auto-
35 matically connecting the reciprocator and the decimal carriage within said zone and disconnecting them without said zone, and means to move said reciprocator relative to said printing carriage.
40 4. In a machine adapted for calculating and horizontal printing: a decimal carriage traveling to locate the calculating point; a printing carriage, traveling to locate the printing point, and including in its travel a zone of horizontal addition; a reciprocator relatively movable to said printing carriage to reciprocate the decimal carriage for the calculating of the horizontally printed numbers and traveling at the same rate as said decimal carriage; a bolt and catch auto-
45 matically connecting the reciprocator and the decimal carriage within said zone and disconnecting them without said zone, and means to move said reciprocator relative to said printing carriage.
50 5. In a machine adapted for calculating and horizontal printing: a decimal carriage traveling to locate the calculating point; a printing carriage traveling to locate the printing point, and including in its travel a zone of horizontal addition; a reciprocator relatively movable to said printing carriage to reciprocate the decimal carriage for the calculating of the horizontally printed numbers and traveling at the same rate as said decimal carriage; mechanism for disconnecting the decimal carriage and the reciprocator when the printing carriage is moved beyond its zone, and means to move said reciprocator relative to said printing carriage.
55 6. In a machine adapted for calculating and horizontal printing: a decimal carriage traveling to locate the calculating point; a printing carriage traveling to locate the printing point, and including in its travel a zone of horizontal addition; a reciprocator relatively movable to said printing carriage to reciprocate the decimal carriage for the calculating of the horizontally printed numbers and traveling at the same rate as said decimal carriage; mechanism for disconnecting the decimal carriage and the reciprocator when the reciprocator is moved to an extreme position, and means to move said reciprocator relative to said printing carriage.
60 7. In a machine adapted for calculating and horizontal printing: a totalizer and master mechanism therefor, traveling relatively to each other to locate the calculating point; a printing carriage traveling to locate the printing point, and including in its travel a zone of horizontal addition; a reciprocator relatively movable to said printing carriage to reciprocate the totalizer or the master mechanism for the calculating of the horizontally printed numbers and traveling at the same rate as said totalizer or master mechanism; mechanism for disconnecting the totalizer or master mechanism from the reciprocator when the printing carriage is moved beyond its zone, and means to move said reciprocator relative to said printing carriage.
65 8. In a machine adapted for calculating and horizontal printing: a totalizer and master mechanism therefor, traveling relatively to each other to locate the calculating point; a printing carriage traveling to locate the printing point; and including in its travel a zone of horizontal addition; a reciprocator relatively movable to said printing carriage to reciprocate the totalizer or master mechanism for the calculating of the horizontally printed numbers and traveling at the same rate as said totalizer or master mechanism; mechanism for the disconnecting of the totalizer or master mechanism from the reciprocator when the totalizer or master mechanism are moved to an extreme position, and

means to move said reciprocator relative to said printing carriage.

9. In a machine adapted for calculating and horizontal printing: a totalizer and master mechanism therefor, traveling relatively to each other to locate the calculating point; a printing carriage traveling to locate the printing point; and including in its travel a zone of horizontal addition; a reciprocator 10 relatively movable to said printing carriage to reciprocate the totalizer or master mechanism for the calculating of the horizontally printed numbers and traveling at the same rate as said totalizer or master mechanism; 15 mechanism for disconnecting the totalizer or the master mechanism from the reciprocator when the reciprocator is moved to an extreme position, and means to move said reciprocator relative to said printing carriage. 20 10. In a machine adapted for calculating and horizontal printing: a decimal carriage traveling to locate the calculating point; a printing carriage traveling to locate the printing point, and including within its 25 travel a zone of horizontal addition; a reciprocator relatively movable to said printing carriage to reciprocate the decimal carriage for the calculating of the horizontally printed numbers and traveling at the same 30 rate as said decimal carriage; a bolt on the reciprocator; a catch on the decimal carriage, the bolt and catch automatically connecting the reciprocator and decimal carriage within 35 said zone and disconnecting them without said zone, and means to move said reciprocator relative to said printing carriage. 40 11. In a machine adapted for calculating and horizontal printing: a totalizer traveling to locate the calculating point; a printing carriage traveling to locate the printing point and including in its travel a zone of 45 horizontal addition; a reciprocator relatively movable to said printing carriage to reciprocate the totalizer for the calculation of the horizontally printed numbers and traveling at the same rate as said totalizer; mechanism 50 for disconnecting the totalizer and the reciprocator when the printing carriage is moved beyond its zone, and means to move said reciprocator relative to said printing carriage. 55 12. In a machine adapted for calculating and horizontal printing: a totalizer traveling to locate the calculating point; a printing carriage traveling to locate the printing point and including in its travel a zone of horizontal addition; a reciprocator relatively 60 movable to said printing carriage to reciprocate the totalizer for the calculation of the horizontally printed numbers and traveling at the same rate as said totalizer; mechanism 65 for disconnecting the totalizer and the reciprocator when the totalizer is moved to an extreme position, and means to move said

reciprocator relative to said printing carriage. 85

13. In a machine adapted for calculating and horizontal printing: a totalizer traveling to locate the calculating point; a printing carriage traveling to locate the printing point and including in its travel a zone of horizontal addition; a reciprocator relatively movable to said printing carriage to reciprocate the totalizer for the calculation of the horizontally printed numbers and traveling 70 at the same rate as said totalizer; mechanism for disconnecting the totalizer and the reciprocator when the reciprocator is moved to an extreme position, and means to move said reciprocator relative to said printing 75 carriage. 80

14. In a machine adapted for calculating and horizontal printing: a decimal carriage traveling to locate the calculating point; a printing carriage traveling to locate the printing point and including in its travel a zone of horizontal addition; a reciprocator relatively movable to said printing carriage to reciprocate the decimal carriage for the calculating of the horizontally printed numbers and traveling at the same rate as said decimal carriage; mechanism including a part mounted on the printing carriage and operating to disconnect the reciprocator and the decimal carriage whenever said printing 90 carriage travels without said zone, and means to move said reciprocator relative to said printing carriage. 95

15. In a machine adapted for calculating and horizontal printing: a decimal carriage 100 traveling to locate the calculating point; a printing carriage traveling to locate the printing point and including in its travel a zone of horizontal addition; a reciprocator relatively movable to said printing carriage 105 to reciprocate the decimal carriage for the calculating of the horizontally printed numbers and traveling at the same rate as said decimal carriage; mechanism including a part mounted on the printing carriage and 110 operating to carry the decimal carriage to an extreme position whenever said printing carriage travels beyond said zone to thereby disconnect the reciprocator and the decimal carriage, and means to move said reciprocator 115 relative to said printing carriage. 120

16. In a machine adapted for calculating and horizontal printing: a decimal carriage traveling to locate the calculating point; a printing carriage traveling to locate the printing point and including in its travel a zone of horizontal addition; a reciprocator relatively movable to said printing carriage to reciprocate the decimal carriage for the calculating of the horizontally printed numbers and traveling at the same rate as said decimal carriage; mechanism including a part mounted on the printing carriage and 125

operating to carry the reciprocator to an extreme position whenever said reciprocator travels beyond said zone, to thereby disconnect the reciprocator and decimal carriage, 5 and means to move said reciprocator relative to said printing carriage.

17. In a machine adapted for calculating and horizontal printing: a decimal carriage traveling to locate the calculating point; 10 a printing carriage traveling to locate the printing point and including in its travel a zone of horizontal addition; a reciprocator relatively movable to said printing carriage to reciprocate the decimal carriage for the 15 calculating of the horizontally printed numbers and traveling at the same rate as said decimal carriage; mechanism including a stop mounted upon the printing carriage and operating to disconnect the reciprocator and 20 decimal carriage whenever said printing carriage travels beyond said zone, and means to move said reciprocator relative to said printing carriage.

18. In a machine adapted for calculating 25 and horizontal printing: a totalizer traveling to locate the calculating point; a printing carriage traveling to locate the printing point and including in its travel a zone of horizontal addition; a reciprocator relatively 30 movable to said printing carriage to reciprocate the totalizer for the calculating of the horizontally printed numbers and traveling at the same rate as said totalizer; mechanism including a part mounted on the printing carriage and operating to disconnect the reciprocator and the totalizer whenever said printing carriage travels without said zone, and means to move said reciprocator relative to said printing carriage.

40 19. In a machine adapted for calculating and horizontal printing: a totalizer traveling to locate the calculating point; a printing carriage traveling to locate the printing point and including in its travel a zone of 45 horizontal addition; a reciprocator to reciprocate the totalizer for the calculating of the horizontally printed numbers; and mecha-

nism mounted on the printing carriage and operating to carry the totalizer to an extreme position whenever said printing carriage travels beyond said zone to thereby disconnect the reciprocator and the totalizer.

20. In a machine adapted for calculating and horizontal printing: a totalizer traveling to locate the calculating point; a printing carriage traveling to locate the printing point and including in its travel a zone of horizontal addition; a reciprocator to reciprocate the totalizer for the calculating of the horizontally printed numbers; and mechanism including a part mounted on the printing carriage and operating to carry the reciprocator to an extreme position whenever said reciprocator travels beyond said zone, to thereby disconnect the reciprocator and 65 the totalizer.

21. In a machine adapted for calculating and horizontal printing: a totalizer traveling to locate the calculating point; a printing carriage traveling to locate the printing point and including in its travel a zone of horizontal addition; a reciprocator to reciprocate the totalizer for the calculating of the horizontally printed numbers; a bolt on the reciprocator and a catch on the totalizer for 70 the connecting of the reciprocator and totalizer; and a rider on the reciprocator and a hill on the framework for disconnecting the reciprocator and totalizer.

22. In a calculating machine, the combination of a traveling carriage, a reciprocating totalizer, a spring to hold said totalizer in a normal position and being adapted to be disconnected from said totalizer, and means to automatically govern the connection of 85 said spring to said totalizer at points determined by the travel of said carriage.

In witness whereof, I have hereunto subscribed my name in the presence of two witnesses.

HYMAN ELI GOLDBERG.
